UNITED STATES PATENT OFFICE

WILLIAM W. REESE, OF WASHINGTON, PENNSYLVANIA, ASSIGNOR TO THE DUNCAN & MILLER GLASS COMPANY, OF WASHINGTON, PENNSYLVANIA, A CORPORATION OF PENNSYLVANIA

DESIGN FOR A GLASS TUMBLER OR SIMILAR ARTICLE

Application filed March 19, 1931. Serial No. 39,164. Term of patent 14 years.

To all whom it may concern:

Be it known that I, WILLIAM W. REESE, a citizen of the United States, residing at Washington, in the county of Washington and State of Pennsylvania, have invented a new, original, and ornamental Design for a Glass Tumbler or Similar Article, of which the following is a specification, reference being had to the accompanying drawings, forming a part hereof.

Figure 1 is a perspective view of a tumbler showing my new design; and

Figure 2 is a fragmentary view showing a projected view of the design.

The design comprises a series of elongated spaced apart mitres having the concave punties between the mitres, as shown.

I claim:

The ornamental design for a glass tumbler or similar article, as shown and described.

WILLIAM W. REESE.

CERTIFICATE OF CORRECTION.

Design Patent No. 84,440.

Granted June 16, 1931, to

WILLIAM W. REESE.

It is hereby certified that error appears in the above numbered patent requiring correction as follows: In the heading to the printed specification, line 6, application clause, for "Application filed March 19, 1931. Serial No. 39,164. Term of patent 14 years" read Application filed April 3, 1931. Serial No. 39,356. Term of patent 7 years; and that the said Letters Patent should be read with this correction therein that the same may conform to the record of the case in the Patent Office.
